DESIGN FOR SUNGLASSES

Aaron Coen, Newark, N. J.

Application September 27, 1948, Serial No. 148,793

Term of patent 3½ years

(Cl. D57—1)

To all whom it may concern:

Be it known that I, Aaron Coen, a citizen of the United States, residing at Newark, New Jersey, have invented a new, original, and ornamental Design for Sunglasses, of which the following is a specification, reference being had to the accompanying drawing, forming part thereof, in which

Figure 1 is a front elevation of the sunglasses, showing the new design;

Figure 2 is a top plan view of the sunglasses; and

Figure 3 is a side elevation of the sunglasses of Figure 1.

I claim:

The ornamental design for sunglasses, as shown.

AARON COEN.
